WHEEL FOR VEHICLES

Rolf Wiener, 43 Richard-Wagner-Strasse,
Gaetringen, Germany

Filed July 31, 1972, Ser. No. 276,304

Claims priority, application Germany Jan. 29, 1972

Term of patent 14 years

Int. Cl. D12—16

U.S. Cl. D12—209

FIG. 1

FIG. 2

FIG. 3

FIG. 1 is a front perspective view of a wheel for vehicles showing my new design;

FIG. 2 is a rear elevational view thereof; and

FIG. 3 is a sectional view of the rim taken along III—III in FIG. 1.

The characteristic feature of my design resides in the configuration of the wheel center.

I claim:

The ornamental design for a wheel for vehicles, as shown and described.
